(57) **CLAIM**

The ornamental design for an automotive wheel, as shown and described.

DESCRIPTION

FIG. 1 is a perspective view of one embodiment of an automotive wheel.

FIG. 2 is a perspective view of another embodiment of the automotive wheel.

FIG. 3 is another perspective view of the automotive wheel.

FIG. 4 is a front elevational view of the automotive wheel.

FIG. 5 is a rear elevational view of the automotive wheel.

FIG. 6 is a side view of the automotive wheel.

FIG. 7 is a side view of the automotive wheel.

FIG. 8 is a side view of the automotive wheel; and,

FIG. 9 is a side view of the automotive wheel.

The broken lines in the drawings are for the purpose of illustrating portions of the automotive wheel that form no part of the claimed design. The dot-dash lines define the bounds of the design and forms no part of the claimed design.
